UNITED STATES PATENT OFFICE.

KARL FRIEDRICH KRANEY, OF GUBEN, GERMANY, ASSIGNOR TO CARL HEINZE
MASCHINENFABRIK A. G., OF GUBEN, GERMANY, A FIRM.

HAT-FORMING MACHINE.

Application filed March 6, 1926, Serial No. 92,661, and in Germany October 8, 1925.

This invention relates to a hat forming machine and more particularly to a machine of such kind, whereby the hair material is picked or divided up by a first or preliminary picking or dividing operation and thereafter by a second or final picking or dividing operation applied subsequently to the former. The invention has for its object to provide a machine of this kind, which for the same working capacity will be of comparatively smaller dimensions and which may be manufactured at a considerably smaller cost.

A further object of this invention is to avoid certain drawbacks inherent to the operation of machines of this kind, which are constructed in the ordinary way. One defect of the known machines consists in the fact that frequently its operation will be disturbed, as known to those skilled in the art, by improper operation of the travelling belt by means of which the hair material, which is divided up by the first or preliminary dividing device, is supplied to the second or final dividing device.

In the heretofore known machines, by reason of the comparatively large width of the travelling belt, which must always be kept under a certain tension in order to evenly and uniformly carry forward the hair, it becomes difficult to drive this belt strictly in a straight line over all its width, that is to say in the direction of its centre plane of symmetry. Also, it frequently happens, that the travelling belt will hit or rub against the guiding bars which serve for guiding the belt on both of its sides, whereby folds will be formed in the travelling belt, as the latter is continuously pressed away in lateral direction. These folds once made cannot be removed and will finally come in contact with the grooved intake or drawing in rollers and thus gradually be worn off, with the result that the travelling belt will be prematurely rendered unfit for service.

Also in case traveling belts are employed, which are protected against the formation of folds by providing closely adjacent wood sticks or the like on the belt, again the objectionable sideward pushing against the lateral guiding bars will take place. In this case also a one sided hitting or rubbing of the travelling belt against the lateral guiding members will have the result, that the retarded side of the belt will remain in the rear with respect to the non-retarded side

thereof. During transit through the guiding rollers these wood sticks will be twisted by reason of the fact, that the ends of the sticks, which are positioned at the free or non-retarded side of the belt will be carried still further forward by the roller, while the sticks at the retarded ends of the belt have not yet approached the driving or guiding roller. In consequence thereof said wood sticks will be gradually loosened, until finally one stick will be entirely separated from the travelling belt and brace itself against one of the intake rollers, whereby the supply of hair will be delayed and in addition to this the entire machine may be eventually heavily damaged.

A further drawback of the heretofore known machines is found in the fact that the said travelling belt, on account of its supporting rollers being entirely enclosed and its surface being fully covered up with hair in its preliminary condition of treatment, cannot well be observed and inspected with regard to its proper mode of operation. Such an inspection of the belt, moreover, even if show holes were provided in the enclosure thereof, would be rendered difficult by the very fact that the position of the belt, which is generally arranged in horizontal or only slightly inclined condition, renders the proper observation of the belt rather difficult.

Machines having a travelling belt between the first and second hair dividing devices also offer difficulties in gaining access to the belt for the purposes of repair. For repairing it will be necessary to remove not only the supports for the upper part of the belt but also the upper guides and even the entire box or compartment serving for the preliminary treatment of the hair.

It is the principal object of this invention to dispense with the travelling belt between the first or preliminary and the second or final dividing devices. This is accomplished by having the hair material, which is divided up by the preliminary dividing device, carried in free motion by means of a stream of air from the first dividing device to the final dividing device. This feature results in important technical and commercial advantages, as is subsequently more fully explained.

In order to more clearly point out the advantages in both structure and mode of op-

eration attained by the novel machine made according to the instant invention, the mode of operation of the heretofore known type of machine employing a traveling belt intermediate the first and final hair dividing devices may be mentioned. In such heretofore known machines the divided or picked hair fibres will adhere properly to the conical hat form only if the latter is in wet condition, and since the air suction employed in such machines for drawing the hair material on to the hat form tends to quickly dry the latter, it is evident that the supply of hair to the form must be begun as soon as the latter is placed in position to receive the same. The operator will therefore place the hair material intended for the formation of a succeeding hat in position on the initial feed belt to be carried thereby through the first dividing device while the preceding hat is being finished upon the wet hat form, and while the hair material for the preceding hat is passing from the first dividing device on the intermediate traveling belt to and through the final dividing device. It follows, therefore, that when the preceding hat is finished, the supply of hair thereto must be stopped. In the heretofore known machines the dividing devices operate continuously and interruption of the operation of the belt and intermediate traveling belt is resorted to for the purpose of interrupting the delivery of hair to the hat form. During the standstill of the intermediate traveling belt the preliminary divided hair material, delivered thereon by the first dividing device for subsequent supply through the final dividing device to a succeeding hat form, will be whirled about by the air agitation caused by the continuously operating first dividing device, with the result that the preliminary divided hair fibres will tend to partly unite with each other or be felted together so as to frequently settle back upon the traveling belt in balled or matted up masses or lumps, so that the work of the first dividing device will be partly nullified, and the tendency to form flakes or dags, which fail to be entirely broken up by the final dividing device, is increased, with consequent formation of blemishes in the final hat forming operation.

In the novel machine according to the instant invention, the starting and stopping of or intermittent operation of hair conveying means is eliminated, and a mode of operation for hair delivery is provided which is complete in itself for each hat formed, and which is so carried on in a continuous manner as to the formation of each hat that opportunity for the formation of blemish producing flakes or dags is avoided.

Besides the afore-mentioned improvements of the supply of the hair there is further attained by this invention an essential

shortening of the length of the machine as well as a reduction of its weight.

Furthermore there will be less space required for mounting the machine, which is important in case a larger number of machines is desired to be employed in a limited space. By this shortening of the length of the machine essential technical and commercial advantages are obtained.

In the drawing, Fig. 1 shows an example of a hat blowing machine according to this invention in a lateral view partly in section,

Figure 2 is a top view taken on Fig. 1, and

Figure 3 a modification of the machine according to this invention, employing only one perforated or sieve-like roller.

In the novel machine made according to this invention, the hair material to be treated is placed in the usual manner upon the endless travelling initial feed belt *b*, which is arranged in front of the first or preliminary teasing or picking roller *a*¹ and conveyed by means of the intake rollers *c*, *c*¹ to said first roller *a*¹, by which it is divided up into fine fiber material.

According to this invention the first picking roller *a*¹ is arranged in the lower portion of an air chamber or conduit *d*, which, in preferred arrangement, extends steeply in upward direction. Through this conduit a stream of air will flow in the direction of the arrow *e*, said air being set in motion by the rapidly rotating picking roller *a*¹ or by a special device suited for this purpose. This stream of air, which enters at the point *f* into the air conduit *d*, will carry with it the hair material in free and unobstructed motion in upward direction. The entrance opening *f* for the stream of air may be enlarged or narrowed in any desired manner, such as for instance by means of a door, slide or the like, not shown in the drawing. This door or slide is adjusted for producing the desired intensity of the stream of air, which is required for the hair material under treatment.

The desired quantity of air may also be obtained by means of special devices, for instance by a draft producing cylinder or the like provided in the rear of the preliminary dividing compartment, by employing a special ventilator pressure pipe, by connecting a suction pipe to the exhauster and the sieve-like roller, said exhauster being always present in machines of this kind, or also by any other suitable auxiliary means for producing a proper draft of the air.

The air conduit *d* may likewise be positioned in oblique or in horizontal direction without in any way affecting the mode of operation.

The conduit *d* is provided with the observation hole or window *g*, through which the motion of the hair may always be conven-

iently inspected, and is further closed up at its upper end by one or more rollers h and h^1 serving to catch up the hair. Of these rollers, as shown in Figs. 1 and 3, at least one should be constructed as a perforated roller serving for the discharge of the air.

These perforated or sieve-like rollers will convey the hair during their rotation to the supply rollers c^2 , c^3 , which convey the hair to the second or final picking roller a^2 .

As shown in Figs. 1 and 3, a perforated or sieve-like roller operates in connection with a catch space i , whose free wall is perforated and provided with a wire netting serving for the discharge of air, said wire netting further serving for retaining and collecting hair dust or fibres, which have eventually been carried away by the sieve-like roller h .

A part of the air, which passes through the conduit d and which carries with it the hair treated by the first picking roller, may also be caused to enter through the sieve-like roller h^1 . The quantity of air partially discharging through the sieve-like roller h^1 may be regulated at will by means of a movable slide l or the like, which may be made to cover up a greater or smaller part of this roller.

The hair material, which is still further divided by the second picking roller a^2 , is finally conveyed in the usual manner by the draft-producing cylinder k and by reason of the suction effect of the exhauster, which is not shown in the drawing, to the rotating conical hat form m .

Upon this hat form the hat will be formed by means of a spraying device as known, said spraying device not being shown in the drawing.

In operation of the novel machine of this invention, the operator, after placing the hat-form in position, deposits hair material on the feed-belt b in sufficient quantity for the formation of the desired hat body. The feed-belt delivers this hair material to the first picking roller a^1 . After passing the first picking roller a^1 , the hair material, as preliminarily loosened up thereby, is floated by the air current in the conduit d to the roller h , or rollers h and h^1 , as the case may be, to be passed thereby through the supply rollers c^2 and c^3 to and through the second picking roller a^2 and thence to the hat form in the usual manner. Since there is no

traveling belt between the first and final dividing devices, but rather the preliminarily loosened or divided hair material is floated in continuous motion from said first to said final dividing device, there is neither opportunity for bunching of the hair due to uneven travel of a conveying belt, nor opportunity for the hair to settle in balled or matted flakes or dags while passing from one picking device to the other, and consequent-

ly the likelihood of producing blemished hat bodies is reduced to a minimum. After enough hair is thus furnished to produce the desired hat body on the hat form, the operator discontinues the deposit of hair material upon the feed-belt b until the preceding hat is finished, the hat form on which the latter is formed is removed and replaced by another hat form, after which the deposit of hair material for a succeeding hat forming operation is made, the machine being run without interruption.

The already above-mentioned advantages of the machine according to this invention may be briefly summarized as follows:—

A traveling belt with driving means and means for putting the same into and out of operation, which latter means is ordinarily provided between the preliminary and the final divider, will be entirely dispensed with. The machine will thereby be simplified to a considerable degree and its weight and the cost of its manufacture will be remarkably reduced.

The preliminary divided and loosened hair, furthermore, will be supplied to the final divider by an essentially quicker motion, than had heretofore been possible. More particularly, this motion of the hair takes place in a direction preferably steeply upward. Also, a balling up or felting of hair material in the machine is entirely avoided according to this invention.

By reason of the approximately perpendicular arrangement of the blowing channel a the length of the machine will be considerably reduced, which will not only be of advantage regarding reduction of weight but also will practically eliminate the disturbing influence exerted by the reciprocating motion of masses. Besides, the motion of the hair may be conveniently observed or inspected.

The time which is required for conveying the divided hair from the point of entrance at b as far as to the conical hat form m is so short that no further preliminary work, such as supplying the hair as early as during the spraying and the exchange of the hat form, will be necessary. By this the refelting of the divided hair will be avoided and the attendance of the machine rendered essentially more easy and considerably simplified.

I claim:—

1. In a hat forming machine having a receiving chamber provided with a hair intake opening and a hat form within said chamber, means for dividing hair material and delivering the same, comprising an air conduit having an air inlet at its lower end, a rotative preliminary hair dividing means at the lower end of said air conduit adjacent to said air inlet, means to feed hair material to said preliminary dividing means, 125
2. In a hat forming machine having a receiving chamber provided with a hair intake opening and a hat form within said chamber, means for dividing hair material and delivering the same, comprising an air conduit having an air inlet at its lower end, a rotative preliminary hair dividing means at the lower end of said air conduit adjacent to said air inlet, means to feed hair material to said preliminary dividing means, 130

a rotative final hair dividing means intermediate the upper end of said air conduit and said intake opening of said receiving chamber adapted to deliver hair through the latter for deposit on said hat form, and means adjacent to said final hair dividing means adapted to both discharge air from the upper end of said air conduit and receive the hair for passage through said final dividing means, said preliminary dividing means being adapted by its rotation to induce an upward flowing air current through said conduit operative to transfer the hair from said preliminary to said final dividing means.

2. In a hat forming machine having a receiving chamber provided with a hair intake opening and a hat form within said chamber, means for dividing hair material and delivering the same, comprising an air conduit having an air inlet at its lower end, a rotative preliminary hair dividing means at the lower end of said air conduit adjacent to said air inlet, means to feed hair material to said preliminary dividing means, a rotative final hair dividing means intermediate the upper end of said air conduit and said intake opening of said receiving chamber adapted to deliver hair through the latter for deposit on said hat form, and rotative means arranged across the upper end of said conduit adapted to discharge the air stream therefrom but to retain and deliver the hair to said final dividing means, said preliminary dividing means being adapted by its rotation to induce an upward flowing air current through said conduit operative to transfer the hair from said preliminary to said final dividing means.

3. A machine as defined in claim 2, having means cooperative with said rotative perforate means to vary the air discharge capacity thereof.

4. In a hat forming machine having a receiving chamber provided with a hair intake opening and a hat form within said chamber, means for dividing hair material and delivering the same, comprising an air conduit having an air inlet at its lower end, a rotative preliminary hair dividing means at the lower end of said air conduit adjacent to said air inlet, means to feed hair material to said preliminary dividing means, a rotative final hair dividing means intermediate the upper end of said air conduit and said intake opening of said receiving chamber adapted to deliver hair through the latter for deposit on said hat form, a pair of

hollow perforate rolls arranged across the upper end of said air conduit adjacent said final dividing means adapted to discharge the air stream therefrom but to retain and deliver the hair to said final dividing means, and a catch chamber having one end in communication with a portion of the perforate surface of one of said rolls, said preliminary dividing means being adapted by its rotation to induce an upward flowing air current through said conduit operative to transfer hair from said preliminary to said final dividing means.

5. In a hat forming machine having a receiving chamber provided with a hair intake opening and a hat form within said chamber, means for dividing hair material and delivering the same, comprising an air conduit having an air inlet at its lower end, a rotative preliminary hair dividing means at the lower end of said air conduit adjacent to said air inlet, means to feed hair material to said preliminary dividing means, a rotative final hair dividing means intermediate the upper end of said air conduit and said intake opening of said receiving chamber adapted to deliver hair through the latter for deposit on said hat form, a pair of hollow perforate rolls arranged across the upper end of said air conduit adjacent said final dividing means adapted to discharge the air stream therefrom but to retain and deliver the hair to said final dividing means, a catch chamber having one end in communication with a portion of the perforate surface of one of said rolls, said preliminary dividing means being adapted by its rotation to induce an upward flowing air current through said conduit operative to transfer hair from said preliminary to said final dividing means, and means to cooperate with the remaining perforate roll to vary the air discharge capacity thereof.

6. A method of operating hat forming machines which consists in dividing the hair in a preliminary dividing device, inducing a stream of air adjacent to said preliminary dividing device and directing the same toward a final dividing device, discharging said stream of air adjacent to said final dividing device while at the same time separating the hair therefrom for passage through the latter device, and then delivering the finally divided hair upon a hat form.

In testimony whereof I have affixed my signature.

KARL FRIEDRICH KRANEY.
